SELF-SOAPING SHAVING BRUSH

Angel Nunez Turnes, Bridgeport, Conn.

Application June 28, 1950, Serial No. 170,780

2 Claims. (Cl. 15—122)

1

This invention relates to improvements in shaving appliances, and is particularly directed to self-soaping shaving brushes.

The primary object of this invention is to provide a shaving appliance including a shaving brush and a soap stick holder carried within a casing in such a manner that either the brush alone may be extended from the casing or the brush and soap stick holder may both be extended.

Another object is to provide a shaving appliance including a shaving brush and soap stick holder arranged so that the soap stick holder may be received centrally in the brush and the brush and soap stick holder both retracted into a casing when not in use to provide a compact and sanitary arrangement for ease in carrying.

A further object is to provide a shaving appliance including a casing, a shaving brush having a hollowed out center and a shaving stick holder receivable in the center of the brush, with improved operating mechanism for individually extending the brush and holder out of the casing.

Still another object is to provide a shaving appliance of the class described which is simple in construction, sturdy and easy to manufacture.

These and other objects, features and advantages of the invention will appear in the following detailed description of a preferred embodiment thereof, which is to be read in conjunction with the accompanying drawing wherein:

Fig. 1 is a side elevational view of a shaving appliance constructed according to this invention, and with a cover installed thereon;

Fig. 2 is a top plan view of the appliance as shown in Fig. 1;

Fig. 3 is a bottom plan view of the appliance of Fig. 1;

Fig. 4 is a vertical sectional view taken through the center of the appliance of Fig. 1;

Fig. 5 is a side elevational view of the device illustrated in Fig. 1, with the cover removed, and with the shaving brush extended, and partially cut away, to expose the soap stick holder which is also extended;

Fig. 6 is a view similar to that of Fig. 5, but with the soap stick holder in retracted position;

Fig. 7 is a transverse sectional view along the line 7—7 of Fig. 4;

Fig. 8 is a transverse sectional view along the line 8—8 of Fig. 4;

Fig. 9 is a transverse sectional view along the line 9—9 of Fig. 4;

Fig. 10 is an elevational view of an element forming a part of the illustrated embodiment;

2

Fig. 11 is a transverse sectional view taken along the line 11—11 of Fig. 10;

Fig. 12 is a side elevational view, partly broken away, of a base for the soap stick holder;

Fig. 13 is a top plan view of the base shown in Fig. 12;

Fig. 14 is a side elevational view of a supporting base for the shaving brush;

Fig. 15 is a top plan view of the supporting base shown in Fig. 14;

Fig. 16 is a side elevational view of another element of the appliance embodying the invention; and

Fig. 17 is a top plan view of the element of Fig. 16.

Referring to the drawing in detail, the shaving appliance embodying this invention is shown to include a cylindrical casing 10 (Figs. 5 and 6) formed with an inwardly bent or curled upper edge 11 and a longitudinally extending slot 12 which opens through the bottom edge thereof. A portion of the periphery of the casing 10 is knurled as at 13 to provide for gripping of the casing during manipulation of the mechanism extending and retracting the shaving brush and soap stick holder which is hereinafter described.

The shaving brush 14 (Fig. 4) includes an annular base 15 within which the bristles 16 are cemented, as by rubber or the like, so that a longitudinal space 17 is formed centrally of the brush. The annular base 15 is provided with threads on its outer surface which engage the internal threads 18 of the cup-shaped brush supporting base 19 (Figs. 14 and 15). Base 19 is provided with a central opening 20 in the bottom thereof and with a raised portion 21 on the outer surface extending substantially half-way there-around. Base 19 is formed to be slidably carried within a rotatable brush operating member 22 (Figs. 10 and 11). The brush operating member 22 includes a disc-shaped bottom 23 formed with serrations 24 on its perimeter to facilitate the gripping thereof, and a cylindrical member 25 extending upwardly from the bottom and formed

45 with a cut-out 26 encompassing substantially half of the circumference of the member 25. The top edge of cylindrical member 25 is rolled outwardly, as at 27, and the diameter of the cylindrical member 25 is such that the rolled top edge will engage closely against the inner surface of casing 10 when member 25 is fitted within the latter. The bottom 23 is further provided with an up-standing annular wall 28, spaced outwardly from the member 25 to receive the bottom edge of casing 10 therebetween, and with a central open-

ing 28 to permit the draining of water from the casing from the bottom thereof.

The brush supporting base 19 is installed within cylindrical member 25, through cut-out 26 at the side of the latter, and with the raised portion 21 of the base fitting in the cutout to form a continuation of the outer surface of cylindrical member 25. Cylindrical member 25 is also provided with a longitudinal slot 30, spaced from the side edge of cut-out 26, and receiving a radially extending pin 31 carried by brush supporting base 19. The coaction of pin 31 and slot 30 permits axial movement of the brush supporting base within cylindrical member 25 and prevents any relative rotation of these parts.

A longitudinally split cylindrical cam member 32 (Figs. 16 and 17) extends around the cylindrical member 25, within the space between the latter and the inner surface of casing 10, and fits between the rolled top edge 27 of member 25 and the upper surface of bottom 23. Cam member 32 is formed with a helical slot 33 which receives pin 31 on the brush supporting base so that as member 25 is rotated, and cam member 32 is held fixed, the brush supporting base will be raised or lowered, depending upon the direction of rotation imparted to member 25.

Also fitting within cylindrical member 25, and movable axially is a base 34 (Figs. 12 and 13) for the soap stick holder. Base 34 includes a disc-like bottom 35 and a pair of spaced upstanding walls 36 and 37. The bottom 35 is formed with a plurality of spaced holes 38 opening between walls 36 and 37, and a central opening 39 opening into the space defined by inner wall 36. The inner wall 36 is formed with internal threads 40 for securing the soap stick holder, hereinafter described, in the base. Base 34 is provided with a radially projecting ear 41 which extends from a boss 42 formed on the outer surface of the outer wall 37.

The soap stick holder supporting base 34 is installed in cylindrical member 25, below supporting base 19, and is angularly disposed so that boss 42 extends through cut-out 26 into the split of cam member 32 and the ear 41 extends through slot 12 of casing 10. Since rotation of base 34 relative to casing 10 is prevented by the engagement of ear 41 in slot 12, and since boss 42 of the base 34 extends into the split of cam member 32, it is apparent that base 34 and cam member 32 are held non-rotatable relative to casing 10, while cylindrical member 25 and base 19 are free to rotate relative to the casing between the angular limits defined by engagement of pin 31 with the opposite ends of slot 33. It will be noted that cut-out 26 is sufficiently large so that pin 31 will engage the opposite ends of slot 33 before the side edges of the cut-out engage against boss 42 on base 34.

The soap stick holder 43 includes a perforated, preferably cylindrical body, open at one end and threaded at that one end into the inner wall 36 of base 34. The other end of the holder 43 is closed by a perforated wall, and the opening in such end wall, the perforations in the side wall and opening 39 in the base are all sufficiently small so that the soap stick 44 will be retained in the holder even after it has been substantially depleted. As seen in Fig. 4, holder 43 extends freely through opening 20 in the bottom of the brush supporting base 19 and into the central space 17 of the brush.

Finally, the appliance embodying this invention includes a cylindrical cover 45, open at its

lower end and having a top wall 46 formed with a central ventilating opening 47. The cover is further formed with a relatively short longitudinal slot 48 (Fig. 1) opening through the lower edge for receiving ear 41 when the soap holder and brush are both retracted into casing 10 and the cover 45 is positioned over the casing to provide a neat and sanitary article that may easily be packed away.

Although no mention has been made of the materials from which the above described parts may be fabricated, it is preferred that, with the exception of the bristles 16 which may be badger hair or nylon by way of example, the parts be formed of a rigid plastic to present a pleasing appearance, resist rusting or corrosion, and provide for inexpensive manufacture. However, it is to be understood that the invention contemplates the use of any other suitable materials, for example corrosion resistant metals.

Passing now to the operation of the preferred embodiment of my invention; when it is desired to use the shaving appliance, cover 45 is removed, and serrated disc 23 is rotated to extend the bristles 16 of brush 14 out of the open top of casing 10. Ear 41 may then be moved axially toward the top end of casing 10 to project the soap stick holder 43 into the central space in the brush (Fig. 5). Water is admitted to the casing through slot 12 in casing 10 and moistens the soap 44 to dissolve the latter and the dissolved soap and water flow through the perforations in the soap holder into the surrounding bristles. The soap may be worked into a lather by brushing onto the face or other portions of the body being shaved, and when sufficient soap has been transferred to the brush, the holder 43 may be withdrawn or retracted into casing 10 (Fig. 6). When the user has finished applying the lather, brush 14 may be retracted into casing 10, by rotating disc 23 in the opposite direction relative to casing 10, and cover 45 applied over the casing top.

Having thus described in detail a preferred embodiment of my invention, it is to be understood that numerous modifications and changes, obvious to those skilled in the art, may be effected without departing from the scope of the invention as defined in the appended claims, and without sacrificing the advantages thereof.

What I claim is:

1. A shaving appliance comprising a cylindrical casing open at the opposite ends thereof and having an axial slot extending a substantial portion of the length thereof, an inner cylindrical member open at the top and rotatable in said casing, said inner cylindrical member having a cut-out extending over a substantially semi-cylindrical portion of the wall thereof and a straight axial slot extending a substantial portion of the length thereof, a base on said inner cylindrical member extending rotatably about the lower end of said casing, an annular brush support axially movable within said inner cylindrical member, a radially extending pin on said brush support slidably received in said axial slot of the inner cylindrical member to prevent rotation of said brush support relative to said inner cylindrical member, a brush on said brush support and defining a central longitudinal space, said brush being longitudinally dimensioned to project from the top of said casing when the brush support is raised and to retract within said casing when the brush support is lowered, an axially split cylindrical member disposed between said inner cylindrical member and said casing and having a helical slot receiving

said radially extending pin, a soap holder support axially movable in said inner cylindrical member below said brush support and independently of the latter, a soap holder on said soap holder support for extension into said central space, and a radial ear on said soap holder support passing through said cutout of the inner cylindrical member and the axial split of the split cylindrical member and extending through the axial slot of said casing to the outside of the latter so that said soap holder support is held non-rotatably relative to said casing and said split cylindrical member is also non-rotatable relative to said casing, said brush holder being formed with a radially raised peripheral portion fitting into said cutout of the inner cylindrical member to prevent lateral movement of said brush holder.

2. A shaving appliance comprising a cylindrical casing open at the opposite ends thereof and having an axial slot extending a substantial portion of the length thereof, an inner cylindrical member open at the top and rotatable in said casing, said inner cylindrical member having a cutout extending over a substantially semi-cylindrical portion of the wall thereof and a straight axial slot extending a substantial portion of the length thereof, a base on said inner cylindrical member extending rotatably about the lower end of said casing, an annular brush support axially movable within said inner cylindrical member, a radially extending pin on said brush support slidably received in said axial slot of the inner cylindrical member to prevent rotation of said brush support relative to said inner cylindrical member, a brush on said brush support and defining a central longitudinal space, said brush being longitudinally dimensioned to project from the top of said casing when the brush support is raised

5 and to retract within said casing when the brush support is lowered, an axially split cylindrical member disposed between said inner cylindrical member and said casing and having a helical slot 10 receiving said radially extending pin, a soap holder support axially movable in said inner cylindrical member below said brush support and independently of the latter, a soap holder on said soap holder support for extension into said central space, and a radial ear on said soap holder support passing through said cutout of the inner cylindrical member and the axial split of the split cylindrical member and extending through the axial slot of said casing to the outside of the latter so that said soap holder support is held non-rotatably relative to said casing and said split cylindrical member is also non-rotatable relative to said casing, said soap holder support and said base of the inner cylindrical member being formed with axial openings to permit drainage of moisture from the interior of the appliance.
